[57] CLAIM

The ornamental design for a regulator of coin selector for automatic vendor, substantially as shown and described.

DESCRIPTION

FIG. 1 is a perspective view of a regulator of coin selector for automatic vendor, showing our new design; FIG. 2 is a left side elevational view thereof;

FIG. 3 is a front elevational view thereof;

FIG. 4 is a top plan view thereof;

FIG. 5 is a bottom plan view thereof;

FIG. 6 is a right side elevational view thereof; and

FIG. 7 is a rear elevational view thereof.

Electrical cable connections are illustrated in broken lines in FIG. 2 for illustrative purposes only and forms no part of my claimed design.

FIG. 1

FIG. 2

FIG. 3

FIG. 4

FIG. 5

FIG. 6

FIG. 7
